CLAIM

The ornamental design for a multipurpose furniture unit, as shown and described.

DESCRIPTION

FIG. 1 is a rear perspective view of a multipurpose furniture unit with the end tables in a closed position, showing my new design;

FIG. 2 is a front elevational view showing the end tables in an alternate use thereof;

FIG. 3 is a rear elevational view showing the end tables in an alternate use thereof;

FIG. 4 is a right side elevational view with the end tables in an alternate use, the left side being a mirror image thereof;

FIG. 5 is a top plan view with the end tables in an alternate use thereof; and,

FIG. 6 is a bottom plan view with the end tables in an alternate use thereof.

FIG. 3

FIG. 2

FIG. 4

FIG. 5

FIG. 6
